UNITED STATES PATENT OFFICE.

CHARLES T. WITTSTEIN, OF CHICAGO, ILLINOIS, ASSIGNOR TO SCHRADER-WITTSTEIN COMPANY, OF CHICAGO, ILLINOIS, A CORPORATION OF ILLINOIS.

DESIGN FOR A SOLITAIRE-GEM-SETTING FINGER-RING.

SPECIFICATION forming part of Design No. 35,745, dated February 18, 1902.

Application filed August 7, 1901. Serial No. 71,277. Term of patent 14 years.

To all whom it may concern:

Be it known that I, CHARLES T. WITTSTEIN, a citizen of the United States, residing at Chicago, in the county of Cook and State of Illinois, have invented and produced a new and original Design for a Solitaire-Gem-Setting Finger-Ring, of which the following is a specification, reference being had to the accompanying drawings, forming a part thereof.

Figure 1 is a view in side elevation of a ring of my new and original design; Fig. 2, a view in edge elevation thereof, and Fig. 3 a plan view thereof.

As shown in the drawings, the leading or material feature of my design consists in a rim-form bezel *a* and open-work *b* supporting the same, said open-work comprising two diametrically opposite (with reference to the rim *a*) standards *c*, lying in the plane of the ring-body *d*, and two diametrically opposite standards *c'*, arranged in a transverse plane, the standards being separated by horizontally-disposed diagonally-extending intersecting perforations *c²c³* and the bases of said standards blending with the body of the ring. The

open-work is upwardly flaring, and the rim *a* likewise has an inner surface, which is upwardly flaring to receive the brilliant.

Minor features of my design are the cuts, crevices, or perforations *f* at the upper ends 30 of the standards, flanked by oppositely-curved scrolls or beads *f'*, and a central vertical perforation *g* at the upper portion of the ring-body and having its axis coincident with the vertical axis of the ring-body. The lower walls 35 of the perforations *c²c³* are curved or dished, and the upper walls or portions thereof are formed by the rim *a*.

Having described my invention, what I claim as new, and desire to secure by Letters 40 Patent, is—

The design of a solitaire-gem-setting finger-ring, as herein shown and described.

In testimony whereof I have signed my name to this specification in the presence of 45 two subscribing witnesses.

CHARLES T. WITTSTEIN.
